CLAIM

The ornamental design for a liftgate for an automobile, as shown and described.

DESCRIPTION

1. Liftgate for an automobile

1.1 is a perspective view of a liftgate for an automobile showing our new design;

1.2 is a front elevation view thereof;

1.3 is a rear elevation view thereof;

1.4 is a left side elevation view thereof;

1.5 is a right side elevation view thereof;

1.6 is a top plan view thereof; and

1.7 is a bottom plan view thereof.
